UNITED STATES PATENT OFFICE

HOWARD L. PAGE, OF CHICAGO, ILLINOIS

PROCESS FOR PRODUCING AN ELECTROCONDUCTIVE SOUND WAVE RECORD

Application filed August 3, 1928. Serial No. 297,333.

This invention relates to improvements in sound records either of the film or pliable tape type or of the rigid type similar for example to the phonograph disc record but will be described herein for purposes of illustration only with reference to the pliable tape type which may be wound on a reel like a motion picture film for example.

It is an object of the invention to provide a sound record, which may be produced and reproduced either separately or synchronously, with the production or the reproduction of motion pictures. Further objects of the invention are the production of sound records which are electroconductive and the reproduction of the sounds recorded on such a record.

It is a further object of the invention to produce a metallic sound record which is electroconductive and which electroconductive properties are utilized in the reproduction of sound from such record.

It is another object of the invention to produce an electroconductive sound record from which a plurality of commercial reproductions may easily be made. With these and other objects in view the invention consists for example in a tape or film on which sound waves are recorded in a novel manner by a special photographic process. The invention further consists of many features and details of construction which will be herein-after more fully described and finally pointed out in the appended claims and which are illustrated on the accompanying drawings which form a material part of this disclosure and in which:

Fig. 1 shows a film provided with one metallic sound wave line, this line lying between two parallel metallic base lines.

Fig. 2 shows a strip of a motion picture film provided with a metallic sound wave line at one side of the picture images on the film and a straight metallic base line beside or adjacent the sound record.

Fig. 3 is a plan much enlarged of a short enlarged piece of the film shown in Fig. 1.

Fig. 4 is a section on the line 4—4 of Fig. 3 showing the metallic deposit on the surface

of a collodion coated film representing the sound record made by my invention.

Fig. 5 is a section similar to that of Fig. 4 illustrating for comparative purposes the distribution of silver particles in a gelatin coated film on which a sound record has been photographed.

Fig. 6 is a diagrammatic plan of a camera for photographing sound records such as shown in Fig. 1.

Fig. 7 is a diagrammatic plan of a camera for simultaneously photographing motion picture images and a sound record on the same film such as shown in Fig. 2.

Fig. 8 is a perspective view of an apparatus suitable for producing duplicates of the sound records shown.

Fig. 9 is a plan view of an original negative gelatin film with two sound wave record lines thereon.

Fig. 10 is a plan view of a positive master film printed from the negative shown in Fig. 9 and utilized in the making of the final sound record of this invention.

The sound recording cameras shown in Figs. 6 and 7 are self-explanatory to those familiar with the art and are shown as an apparatus for producing the original sound negative which is developed in the usual way and becomes the negative which is fixed in hyposulphite of sodium solution and dried in a suitable manner.

Fig. 9 shows a developed negative 40n of a sound wave film. The sound wave formation appears opaque thereon in the clear gelatin coating of the film. From this negative a positive film 40m Fig. 10 is printed by the ordinary contact printing method on the usual positive gelatin coated film. This positive sound record allows light to pass through it exactly where the original sound wave photograph was and this film is used as a master film for the production of commercial sound record films.

The commercial sound record films are produced in the apparatus shown in Fig. 8. and when finished these records have the sound wave lines and the base lines thereon in the form or nature of a metallic deposit on the surface of the film. The sound record

film material does not need to be transparent for reproduction of sound waves; I have used paper reinforced by cloth with good success. Only films 60 shown in Fig. 7 which have 5 also a motion picture imprinted thereon require transparent film and these only for projection of the picture.

The process and apparatus for producing 10 metallic sound wave lines from the positive master film is as follows:

In a box-like housing 61, (see Fig. 8) a lamp 62 is mounted in front of a concave reflector 63 which concentrates the light from the lamp 62 onto a lens system 64 and onto 15 the positive master film 40m which is carried by suitable reels 65 and 66. The light after passing through positive master film 40m is focussed through a narrow slot 67a by a lens system 67 onto a sensitized surface such as 20 the face of film 70. This film 70 need not be transparent as mentioned before nor is a gelatin coating required.

I have secured excellent results by coating 25 the surface of the film 70 with other light sensitive materials such as for example a coating of collodion in which iodides or bromides of either or both cadmium or ammonium have been dissolved. While I secure good results with these materials, nevertheless, others 30 which act in a similar way may be employed. The film strip 70 with its prepared surface is held on a storage reel 68 in the lower part of housing 61 and passes from there under roller 69, rotatably mounted in a trough 71. 35 This trough contains a solution of silver nitrate of suitable strength to react with the bromides or iodides carried by the collodion or other vehicle. In practice a nitrate solution of thirty grains of silver nitrate to the 40 ounce of water has been found satisfactory. The film then passes over a roller 72 and while still wet receives the developable light impression from lamp 62 which has passed through master film 40m bearing the sound wave line thereon. Reel 65 and roller 73 are 45 suitably connected by a chain drive causing them to rotate synchronously either at the same speed or at different speed ratios. If desired, however, the film may first be dried and then 50 a contact print made from the master film 40m, the exposure of the film while wet, i. e., before drying as above described being merely by way of illustration. Such dry collodion films are more fully described by E. J. Wall 55 in his "Photographic Emulsions", 1929, page 112.

Film 70 after passing over roller 73 then passes under a roller 74 rotatably mounted in trough 75 which contains a solution of 60 ferrous sulphate and acetic acid which develops the image of the sound wave line on the film. I have obtained good results by the use of a developer composed of thirty grains of ferrous sulphate to one ounce of water and twenty minims of acetic acid. The

record film 70 then passes over a roller 76 and under roller 78 which latter roller is mounted in trough 77 containing a fixing solution of sodium hyposulphite which dissolves the unexposed silver particles, whereupon the film 70 passes out of housing 61 over roller 79 and under roller 80 to any suitable drying apparatus.

That part of the record film 70 so produced which has been exposed as precipitated and developed thereon metallic silver, thereby producing an electroconductive metallic record of the sound wave on the film as shown in enlarged section in Fig. 4.

This action is covered in greater detail by 80 Meldola in his work "The Chemistry of Photography" 4th ed., 1913, page 159; also by Abney in his "Instruction in Photography" 11th ed., 1905, page 32.

Fig. 5 represents a sectional elevation 85 through a celluloid support 82 which carries the usual gelatine emulsion 83 and contains materials sensitive to light held in suspension within the emulsion. When developed with the usual alkaline developer the opaque 90 particles representing the images are distributed or diffused throughout the total thickness of the film as indicated at c1, d2 and d3. The electrical conductivity of such a record 95 is negligible, the metallic particles being insulated from each other by the gelatine. The use of the acid developer above referred to is, therefore, of great and material advantage in that it enables me to produce an electroconductive sound record as distinguished from 100 a sound record which is not electroconductive, the production of an electroconductive sound record being a desideratum of my invention.

Fig. 4 shows a similar cross section through 105 the same sound record film of Fig. 3 when produced by my method. The support 82 carries a coating of collodion 84 upon the surface of which lies the image of the sound wave "c" and base lines "d"—"d1" as a coating 110 of metallic silver the particles of which are adjacent to each other and so close that they form an excellent conductor of electricity, and what is of greatest importance the sound wave and base lines are all on the surface of the coating forming accessible contact surfaces which are insulated from each other by the collodion coating 84 between them and the support 82 below them.

The metallic deposit on the supporting base 120 may be increased in thickness if desired by redevelopment with a liquid containing a metal in solution which can be precipitated therefrom and deposited upon the metallic image. While a certain percentage of gelatine may be incorporated in the carrier or 125 supporting base and such a film treated with the developers above referred to, the results do not seem to be improved.

The method for reproduction of sound from 130 my metallic sound record is a very simple one

as the metal of the record itself is capable of varying the current in an electric circuit.

Having thus described my invention, what I claim as new and desire to secure by Letters 5 Patent is:

1. The process for producing an electro-conductive sound wave record which consists in photographically recording sound waves upon a transparent film, producing a negative 10 image of the sound waves by developing said film, printing a positive therefrom, reprinting said record upon a dielectric tape having a coating containing a metallic compound, and precipitating the metal from said 15 compound on to the surface of said tape by photographic development.

2. The process for producing an electro-conductive sound wave record which consists in photographically recording sound waves 20 upon a transparent film, producing a negative image of the sound waves by developing said film, printing a positive record therefrom and reprinting said record upon a non-conductive tape having a liquid coating containing 25 silver in solution and by depositing the silver from said solution upon the surface of said tape by photographic development.

Signed at Chicago, in the county of Cook and State of Illinois, this 25th day of July, 30 A. D. 1928.

HOWARD L. PAGE.
